J. ROCK.

Shifting-Rail.

No. 68,904.

Patented Sept. 17, 1867.

United States Patent Office.

JAMES ROCK, OF HASTINGS, ENGLAND.

Letters Patent No. 68,904, dated September 17, 1867.

IMPROVEMENT IN CARRIAGES.

The Schedule referred to in these Letters Patent and making part of the same.

TO ALL TO WHOM IT MAY CONCERN:

Be it known that I, JAMES ROCK, of Hastings, England, carriage-builder, have invented or discovered certain "Improvements in Carriages and Wagons with Folding Heads or Coverings;" and I do hereby declare that the following is a true and exact description thereof, reference being had to the annexed drawing and to the letters and figures marked thereon, that is to say:

My invention consists in applying springs made of steel, India rubber, or other suitable material, either separately or in connection with hinges or joints, to the heads or coverings of landaus and other carriages and wagons, made to open and shut, (whether such carriages or wagons be used for the conveyance of passengers or goods on common roads or on railroads, for the purpose of raising or closing such heads or coverings, or assisting to raise or close them, and whether such raising or closing be done simply by hand or with the aid of weights, levers, screws, or other machinery. I place these springs, made of any convenient shape, so that the moving parts of the heads or coverings draw, press, or rest upon them when lowered, the springs thus counterbalancing the weight of those parts and giving them a tendency to rise when required.

I show one method of applying these springs in Figures 1 and 2 of the annexed drawings, which represent in section the back half of the framework of a carriage called a landau.

Figure 1 shows the half of the landau head thrown open or back.

Figure 2 shows it closed or raised, and, as seen from the opposite side of the carriage. *a a'* are springs made of steel, fixed to the elbow-framing of the body. *b b'* are cranked levers working on pivots or centres *c c'*, also fixed to the elbow-framing. *d d'* are connecting-rods, which connect the springs with the shorter arms of the cranked levers, causing the longer arms of those levers to press against the pillars *e e'* of the head when the head is thrown open. The cranks of these levers are so arranged that when the head or half-head, as the case may be, is thrown quite open the cranks are so near to the dead-point that the weight of the head-framing overcomes the strength of the springs, and the head remains open until it is required to be closed, when a slight upward pressure or force applied to the frame of the head brings the springs into action and the head closes. In order to close the two pieces marked *f f'*, which, when they meet, form the upper part of the door, as is well understood, I make the hinges at *g g'*, as shown at *h*, Figure 3, with a square hole in the eye of that half of the hinge which is fixed to *f f'*. Into this hole I insert a pin or prop, (shown in Figure 4,) to serve as the upper prop or centre for the usual outside sustaining joint *l*, used to support such heads when closed. The part of the prop *i* which is received in the eye of the outside joint *l* is made with an angle-tooth or feather, as shown in fig. 4, and therefore, in order to give more motion to the parts *f f'* than would be given by the motion of the joints *g g'* and *l*, in lowering the head, so as to let them fall flat, the eyes of the outside joint *l* should be made as shown by the full line in Figure 5. I do not confine myself to the use of one angle-tooth or feather, nor to the particular form shown in fig. 4, but I make the prop *i* of any form that will communicate motion from the joint *g g'* to the part *f*, and at the same time, by allowing space in the eye of the outside joint *l*, allow the part *f* the additional motion before described. In order that a person sitting inside the carriage may most easily raise the head, I make or fix handles, holders, pulls, or tassels into the middle hoop-sticks of the head or the hoop-sticks next to them. By pulling these handles, holders, pulls, or tassels, the head may be easily raised, and when so raised the outside joints may be set or fastened on the inside by means of the props and framework in the manner before described, or by means of levers attached or fitted to the props, such props being made of sufficient length and of proper shape to receive such levers inside. In some cases I use weights, instead of or in addition to springs, to counterbalance the weight of the moving parts of carriage-heads or coverings, attaching the same to the shorter arms of the cranked levers before described. By connecting two of these levers by means of a cross-bar passing under the seat of a carriage the weight of the person or persons sitting on the seat may be used for raising the head.

My invention is adapted alike for carriage-heads covered with flexible material, and for any kind of folding head, whether of solid or jointed woodwork and panelling or with open framework filled in wholly or in part with fixed or movable glasses. In applying the springs to a half-headed carriage, a phaeton or barouche for instance, the levers or springs are generally made to press against the front hoop-stick of the head, which in this case corresponds with the perpendicular *e* of the landau head, as shown in fig. 2.

What I claim, and desire to secure by Letters Patent, is—

The employment of springs or weights, substantially as hereinbefore described, to counterbalance the movable parts of folding carriage or wagon-heads or coverings, in order to raise or close, or to assist in raising or closing, such heads or coverings.

I also claim the combination, as well as the arrangement, of the bent levers *b b'*, the connecting-rods *d d'*, and the springs *a a'*; also their combination with the jointed prop-bars *l l*, the carriage body, and the movable back or part *e* hinged thereto.

I also claim, in combination with the carriage body, its joint-bars *l l*, movable back *e e'*, and top piece *f f'*, the means or mechanism, substantially as described, or the equivalent thereof, for effecting the movement of the joint-bars, so as to close their joints, by turning the part *f f'* down into a horizontal position, such means being the angular teeth or feather *k k* of the prop-pin and the elongated eye of the upper joint-rod *l*, the whole being as shown in figs. 4 and 5, and as hereinbefore specified, the prop-pin *g'* being fixed or applied to the part *f f'* so as to turn or be movable therewith.

JAMES ROCK.
